United States Patent Office

Des. 222,213
Patented Oct. 5, 1971

222,213

HAND GRIP OR SIMILAR ARTICLE

Douglas C. Rumaner, Oakland, N.J., assignor to Air Products and Chemicals, Inc., Allentown, Pa.

Filed Mar. 20, 1969, Ser. No. 16,348

Term of patent 14 years

Int. Cl. D12—14

U.S. Cl. D90—11

FIG. 1

FIG. 2

FIG. 3

FIG. 4

FIG. 5

FIG. 1 is a side elevational view of a hand grip or similar article showing my design, the opposite side of the hand grip having the same overall appearance;

FIG. 2 is a bottom plan view thereof;

FIG. 3 is a top plan view thereof;

FIG. 4 is a front elevational view thereof; and

FIG. 5 is a rear elevational view thereof.

The ornamental surfaces of the hand grip are covered with fiber flock.

I claim:

The ornamental design for a hand grip or similar article, as shown and described.
